(57) **CLAIM**

The ornamental design for a display screen or portion thereof with animated graphical user interface, substantially as shown and described.

DESCRIPTION

FIG. 1 is a front view of a first image of a display screen or portion thereof with an animated graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; and, FIG. 7 is a front view of a seventh image there.

The broken lines showing a display screen or portion thereof and elements of the graphical user interface illustrate portions of the article, and form no part of the claimed design. The appearance of the image transitions sequentially between the images shown in FIGS. 1-7. The process or period in which an image transitions to another image forms no part of the claimed design.
